UNITED STATES PATENT OFFICE.

BERT L. CAMPBELL, OF CHICAGO, ILLINOIS.

AUTOMATIC CUT-OUT.

1,422,923.

Specification of Letters Patent.

Patented July 18, 1922.

Application filed February 20, 1920. Serial No. 360,149.

To all whom it may concern:

Be it known that I, BERT L. CAMPBELL, a citizen of the United States, and a resident of the city of Chicago, in the county of Cook and State of Illinois, have invented a new and useful Improvement in Automatic Cut-Outs, of which the following is a full, clear, and exact description.

My invention relates to automatic cut-outs which are primarily designed for breaking the circuit between a generator and a storage battery which the generator is charging, when for any reason the current from the generator falls below a predetermined minimum or reverses.

A further object of my invention is to provide a cut-out of the type described which is not liable to get out of order, thereby eliminating any danger of the discharge 20 of the storage battery by cutting off the current at the proper time.

A further object of my invention is to provide a cut-out in which the making or breaking of the circuit is effected instantaneously, due to a novel arrangement of parts.

A further object of my invention is to provide a device which is simple in construction and operation, and in which there 30 is no danger of burning out, due to the fact that a permanent magnet is used in lieu of an electro-magnet, for directly operating the switch arm, an electro-magnet being liable to burn out at any time.

A further object of my invention is to provide a device in which the permanent magnet is recharged by the flow of the current through the cut-out, thereby insuring the long life of the device.

Other objects and advantages will appear in the following specification, and the novel features of the invention will be particularly pointed out in the appended claims.

My invention is illustrated in the accompanying drawings, forming part of this application, in which—

Figure 1 is a diagrammatic view of an arrangement for charging a storage battery, showing the circuit breaker in circuit there-with.

Figure 2 is a sectional view through the casing of the circuit breaker, showing the parts in position when the circuit is broken, and

Figure 3 is a section along the line 3—3

of Figure 2, looking in the direction of the arrows.

In carrying out my invention, I provide a casing 1 which may be made of any suitable non-magnetic material. Pivotal 60 mounted at 2 on a bracket 3 on the interior of the casing is a permanent magnet 4 of the horse shoe type. The ends of this magnet are arranged to rest on an armature 5, as shown in Figure 3, when the cut-out is 65 in position to open the circuit. Rigidly secured to the interior of the frame 1 is an electro-magnet having a U-shaped core 6 and a central winding 7. An armature 8 is designed to rest on the top of the U-shaped 70 core 6 when the circuit is open. The armature 8 and the permanent magnet 4 are rigidly connected together by a non-magnetic connection 9 having a handle 10. In the drawings, I have indicated the non-mag- 75 netic connection 9 as being provided with lugs or tongues 11 and 12 arranged to enter the magnet 4 and the armature 8 respectively for securing the parts together. Any other suitable means of forming this con- 80 nection might be used.

Secured to the interior of the casing 1 is a contact 13 which is connected with a binding post 14 by means of a conductor 15. A second binding post 16 is connected to one 85 end of the coil 7. The opposite end of the coil is connected to a contact 17 similar to the contact 13 and carried by an arm 18 which is pivotally mounted at 19 on a portion of the casing 1. As will be seen from 90 the drawing, the arm 18 is bent at 20, and at this point a spiral spring 21 is attached, the other end of the spiral spring being secured to an extension 22 of the connecting member 9. An arm 23 is secured to the 95 extension 22 and is provided with a laterally extending portion 24 arranged to overlie the arm 18 between its pivotal point 19 and the point 20 at which the spring 21 is connected.

From the foregoing description of the various parts of the device, the operation thereof may be readily understood. In Figure 1, I have shown a diagrammatic circuit arrangement for charging a storage battery. 105 In this figure, an engine E drives a dynamo D for charging a storage battery B. In circuit with the dynamo and the battery is the coil 7 of the cut-out. The permanent magnet 4 is connected with a movable con- 110

tact so as to close the circuit through the coil 7 of the electro-magnet. In charging the storage battery, the engine E is run in the ordinary manner, and the handle 10 of the cut-out is pushed upwardly, thereby swinging the permanent magnet 4 toward the electro-magnet 6 and away from the armature 5, the armature 8 moving away from the electro-magnet. The point at which the spring 21 is connected to the extension 22 will move so as to bring the spring 21 on the opposite side of the pivotal point 19 of the arm 18. As the spring passes the center, it will suddenly snap the arm 18 into position to bring the contacts 17 and 13 together. Momentarily there will be a flow of current from the storage battery through the dynamo, but when the latter gets up to speed, the current will now flow from the dynamo through the coil 7 and through the storage battery. This current tends to aid in the magnetization of the permanent magnet. The permanent magnet is held by the electro-magnet so as to keep the contacts 13 and 17 closed, as long as the current is flowing through the electro-magnet in the direction to charge the battery B.

When the current from the generator D reaches a predetermined minimum or reverses, then there is repulsion between the electro-magnet and the permanent magnet, but there is attraction between the permanent magnet 4 and the armature 5, as well as between the electro-magnet and the armature 8. These combined forces tend to suddenly cause the movement of the permanent magnet and the armature 8 downwardly. The spring 21 is now brought into a position on the opposite side of the pivotal point 19 of the arm 18, thus causing a snap action for opening the contacts 17, and 13, and thus breaking the circuit through the coil 7. In order to insure the opening of the contacts, the arm 23 is extended as stated, and the lateral portion 24 positively engages the arm 18 to open the contacts.

A cut-out of the type described has several important advantages over those forms of cut-outs in which only electro-magnets having fine windings are used for operating the switch arm. It often happens that, owing to excessive current, these fine windings will burn out, but with the permanent magnet there is no danger of this happening, so that the cut-outs will always work to break the circuit as long as the permanent magnet retains its magnetism. In view of the fact that it is subject to the magnetizing influence of the electro-magnet during the charging of the battery, it is obvious that the permanent magnet will retain its charge indefinitely.

A further advantage lies in the fact that no delicate balance is necessary in the present device. Where the current is reversed

in the coil 7, there is always a repulsion caused between the electro-magnet and the permanent magnet. In cut-outs in which two coils are used, a change in the direction of the current may, under certain circumstances, cause an attraction instead of repulsion, and thereby defeat the other purposes of the device by causing the contacts to be held together instead of being separated.

The device is relatively simple in construction, has few parts, and is not liable to easily get out of order.

I claim:

1. A cut-out comprising a stationary electro-magnet, a permanent magnet disposed within the field of the electro-magnet and movable toward and away from the latter, an armature on the opposite side of said permanent magnet from said electro-magnet, an armature on the opposite side of said electro-magnet from said permanent magnet, means for connecting said last named armature with said permanent magnet to move with the latter, a stationary contact, a movable contact associated therewith, and means connected with said first named means for moving said movable contact toward and away from said stationary contact.

2. A cut-out comprising a stationary electro-magnet, a permanent magnet disposed within the field of the electro-magnet and movable toward and away from the latter, an armature on the opposite side of said permanent magnet from said electro-magnet, an armature on the opposite side of said electro-magnet from said permanent magnet, means for connecting said last named armature with said permanent magnet to move with the latter, a stationary contact, a movable contact associated therewith, means connected with said first named means for moving said movable contact toward and away from said stationary contact, said last named means comprising a pivoted arm for said movable contact, and a spring connected at one end with said pivoted arm and at the other end with the connecting means between the permanent magnet and the second named armature.

3. In a cut-out, a casing, an armature carried thereby, a permanent magnet pivotally connected to a portion of the casing and arranged to normally rest on said armature, an electro-magnet secured to said casing above said permanent magnet, a second armature disposed above said electro-magnet, means for rigidly connecting said second named armature and said permanent magnet together, a stationary contact, a movable contact in circuit with said electro-magnet, and means for connecting said movable contact with said first named means, for causing the movable contact to snap into or out of engagement with said stationary contact during the movement of said permanent

magnet toward or away from said electro-magnet.

4. In a cut-out, a casing, an armature carried thereby, a permanent magnet pivotally connected to a portion of the casing and arranged to normally rest on said armature, an electro-magnet secured to said casing above said permanent magnet, a second armature disposed above said electro-magnet, means for rigidly connecting said second named armature and said permanent magnet together, a stationary contact, a movable contact in

circuit with said electro-magnet, means for connecting said movable contact with said first named means, for causing the movable contact to snap into or out of engagement with said stationary contact during the movement of said permanent magnet toward or away from said electro-magnet, and a handle secured to the connecting means between the permanent magnet and the second named armature.

BERT L. CAMPBELL.
